SPEED RESPONSIVE APPARATUS

Herbert L. Bone, Pittsburgh, Pa., assignor to The
Union Switch & Signal Company, Swissvale,
Pa., a corporation of Pennsylvania

Application May 17, 1935, Serial No. 22,029

11 Claims. (Cl. 175—355)

My invention relates to speed responsive apparatus.

An object of my invention is the provision of novel and improved speed responsive apparatus which is actuated by electrical means, and by which an unsafe indication due to loss of power or breakage of a part is avoided.

Speed responsive apparatus embodying my invention is particularly suitable for, although in no way limited to, use in connection with speed control systems for railway trains.

I will describe several forms of apparatus embodying my invention, and will then point out the novel features thereof in claims.

15 In the accompanying drawing, Fig. 1 is a dia-grammatic view illustrating one form of apparatus embodying my invention. Fig. 2 is a dia-grammatic view of a second form of apparatus embodying my invention, and Figs. 3 and 4 are dia-grammatic views of modifications of the apparatus of Fig. 2 and which also embody my invention.

Similar reference characters refer to similar parts in each of the several views.

25 Speed responsive apparatus embodying my invention embraces a suitable speed responsive circuit interrupting means and a time limit electromagnetic means adapted to come into action a short period after the conditions actuating it have begun to exist. As shown in Fig. 1, the circuit interrupting means is a commutator, designated as a whole by the reference character C1, and the time limit electromagnetic means consists of two relays R1 and R2 of the direct current neutral type. The shaft 1 of the commutator C1 is operatively connected with a member the speed of whose movement it is desired to determine through the medium of any suitable drive mechanism such, for example, as a train of gears not shown. When the apparatus is utilized to control the circuits of a speed control system for railway trains, the shaft 1 is preferably operatively connected with an axle of the vehicle on which the apparatus is mounted, with the result that the speed of rotation of shaft 1 is in accordance with the speed of the railway train. A contact brush 2 is rigidly mounted on the shaft 1 for rotation therewith and is adapted to engage three annular segments 3, 4 and 5, the arrangement being such that the segment 3 is a complete ring and continuously engages the brush 2, but the segments 4 and 5 span only a little over 180° and alternately engage the brush 2. It follows that with the shaft 1 stationary, electrical connection is continuously completed between the segment 3 and

one or the other of the segments 4 or 5, depending upon the position of the contact brush 2, but that with the shaft 1 rotated, electrical connection is alternately completed between the segment 3 and the segments 4 and 5, the duration which the connection is completed in each case being dependent upon the speed of rotation of the shaft 1, and hence, in turn, dependent upon the speed of the driving member. It is to be understood, however, that my invention is not limited to any specific 10 form of circuit interrupting means and the commutator C1 is shown for illustration only. It is clear that the commutator C1 may be constructed with the segments 3, 4 and 5 mounted rigid on the shaft 1 for rotation therewith, and the contact brush 2 held stationary should it seem desirable to do so.

15 The commutator C1 controls the energizing circuits for the relays R1 and R2, the arrangement being such that the circuits are alternately opened and closed with rotation of the shaft 1. The segment 3 is connected over wire 6 with one terminal of any convenient source of direct current such as a battery 7, and which battery is preferably of a predetermined given voltage. The other terminal of battery 7 is connected with one terminal of the operating winding of each of the relays R1 and R2 over wires 8 and 9, respectively. The second terminal of the operating winding of relay R1 is connected over wire 10 with the segment 5, and the second terminal of the operating winding of relay R2 is connected over wire 11 with the segment 4. Consequently, when brush 2 is in the position to engage the segment 4, current flows from the battery 7 over wire 6, segment 3, brush 2, segment 4, wire 11, operating winding of relay R2, and wire 8 back to the battery 7, and the relay R2 is energized, the potential difference across the terminals of the relay R2 being substantially the full voltage of the battery 7 since the ohmic resistances of wires 6, 8 and 11, and the contact resistance of brush 2 with segments 3 and 4 are negligible. When the brush 2 is moved around and engages the segment 5, current flows from the battery 7 over wire 6, segment 3, brush 2, segment 5, wire 10, operating winding of relay R1, and wire 9 back to the battery 7, and relay R1 is energized, the potential difference across the terminals of the relay R1 being substantially the full voltage of the battery 7 since the ohmic resistance of the circuit other than that of the operating winding of the relay is negligible. When the brush 2 is rotated in response to rotation of shaft 1, the relays R1 and R2 are alternately supplied with current, the duration of each 55

current impulse being in accordance with the speed of rotation of shaft 1. It is to be noted that at least one of the relays R₁ and R₂ is always supplied with current whatever the position of brush 2, since the segments 4 and 5 are made to slightly overlap, as explained hereinbefore. When the brush 2 is in a horizontal position, as viewed in Fig. 1, both relays are supplied with current in parallel.

10 The relays R₁ and R₂ are each provided with a circuit controlling armature in the usual manner, the armature 12 of relay R₁ being adapted to be raised into engagement with a front contact 13 when the relay is energized, and to drop 15 out of engagement therewith when the relay is deenergized. In like manner, the armature 14 of relay R₂ is adapted to be raised into engagement with a front contact 15 when the relay is energized, and to drop away from engagement 20 therewith when the relay is deenergized.

As set forth hereinbefore, the relays R₁ and R₂ constitute a time limit electromagnetic means adapted to come into action a short period after the conditions actuating it have begun to exist, 25 and to this end, each relay R₁ and R₂ is provided with slow pick-up characteristics. That is to say, the armature 12 of relay R₁, for example, is not raised into engagement with the front contact 13 until a predetermined time interval subsequent to initiating the energization of the relay by supplying current to its operating winding. Likewise, the armature 14 of relay R₂ is not raised into engagement until a predetermined time interval subsequent to initiating the energization of that relay by supplying current to its operating winding. In other words, the relays R₁ and R₂ each become effective to operate its respective armature a short period after current is initially supplied to the operating winding of the relay. The time delay in operating the armature is preferably the same for both relays R₁ and R₂. Such time delay in pick-up may be accomplished in any convenient manner, several arrangements being well-known in the art for 40 providing a direct current relay with slow pick-up characteristics.

In addition to being provided with slow pick-up characteristics, the relays R₁ and R₂ are each provided with relatively high pick-up characteristics. For example, the relay R₁ is so proportioned and adjusted that the tractive effort necessary to raise the armature 12 into engagement with the front contact 13 is produced when the value of a current flowing in its winding is, say, 55 75% of the ultimate current value resulting from a potential difference across the terminals of the relay equal to the full voltage of the battery 7. Likewise, the pick-up current of relay R₂ is approximately 75% of the ultimate current effected 60 when the full voltage of the battery 7 is impressed across the terminals of the relay. The relays R₁ and R₂ possess two constants—resistance and inductance. Due to inductance, the current resulting from a voltage impressed across 65 the terminals of the operating winding does not at once rise to the value ultimately reached, that is, the value as indicated by Ohm's law. It follows that with the brush 2 stationary at the position illustrated in Fig. 1, the relay R₂ is supplied 70 with current the ultimate value of which is equal to that produced by the full voltage of the battery 7, as determined by the resistance of the relay, since the inductance delays the building up of the current for a relatively short period only.

75 Under this condition, the energization of the re-

lay R₂ is sufficient to attract the armature 14 and raise it into engagement with the front contact 15 at the expiration of the slow pick-up period. If the brush 2 is rotated at a speed such that the time interval the brush 2 makes engagement with the segment 4 during a half revolution is a little greater than the slow pick-up period of relay R₂, the armature 14 is raised into engagement with contact 15 during this half revolution of the shaft 1 since the time constant resulting from inductance is less than the slow pick-up period and the ultimate value of the current as indicated by Ohm's law is effected for a sufficient length of time. During the half revolution the brush 2 breaks engagement with the segment 4, 10 the energization of relay R₂ dies away to substantially zero and the armature 14 is released. Hence, at such speed of shaft 1 the relay R₂ is picked up and released once each revolution of the shaft 1. In the event the brush 2 is rotated 15 at a speed such that the duration of the connection between the segments 3 and 4 by brush 2 is slightly less than the slow pick-up period of relay R₂, the armature 14 remains down out of engagement with the contact 15. Under this 20 condition of speed, the time interval between two successive impulses is sufficient for the energization of the relay to die away to substantially zero, notwithstanding the inductance causes a slight delay in the dying away of the current. Again, 25 if the speed at which the brush 2 is rotated is relatively high, and rapid impulses of current are supplied to the winding of relay R₂ and build up the magnetism in the magnetic circuit, the average value of the current flowing in the operating 30 winding, however, does not reach the 75% pick-up value due to the inductance of the relay, and hence the armature 14 is not raised into engagement with contact 15 at such relatively high speeds. In other words, there is a critical speed 35 above which the relay R₂ is not picked up, and below which the relay is alternately picked up and released, while at zero speed the relay is steadily energized in case the brush 2 stops at a point where it makes engagement with the segment 4, 40 and the relay is deenergized in case the brush 2 stops at a point where it is out of engagement with the segment 4.

Since the relay R₁ is proportioned and adjusted similar to relay R₂, the operation of the 45 relay R₁ in response to the different speed conditions of brush 2 is the same as just explained in connection with relay R₂, except for the fact that the circuit for the relay R₁ is governed during the opposite half revolution of brush 2. 50 The speed of shaft 1 below which the relays R₁ and R₂ are picked up is hence determined by the pick-up time provided for the relays. For example, if it is desired to operate the relays R₁ and R₂ at speeds up to ten revolutions per minute 55 of the shaft 1, that is, one revolution every six seconds, the pick-up time would be three seconds since each relay is energized during one-half of each revolution. Thus, at all speeds below ten revolutions per minute, each relay would be 60 picked up while its circuit is closed by the brush 2, but that at all speeds above ten revolutions per minute both relays would remain down. At zero speed one or the other of the relays R₁ or R₂ would be picked up, and in the case the 65 brush 2 should stop at the horizontal position, as viewed in Fig. 1, both relays would be picked up.

The relays R₁ and R₂ may be utilized to control indication and control devices to determine whether or not the driving member is moving 70

at all, or is moving above or below a predetermined critical speed. As here shown, relays R1 and R2 govern an indication lamp 16 and a control magnet 18 by virtue of two simple circuits, 5 both of which circuits include a battery 17 and one of which includes the contact 12-13 of relay R1 and the other of which includes the contact 14-15 of relay R2. Hence, the lamp 16 is steadily illuminated and the control magnet 18 is 10 steadily energized when the speed of shaft 1 is zero, since at zero speed at least one of the relays R1 or R2 is steadily picked up. When the speed of shaft 1 is not zero but is below the critical speed, and the relays are alternately picked 15 up and released, the lamp 16 is flashed and the magnet 18 is intermittently supplied with current. When the speed is above the critical speed and neither relay is picked up, the lamp 16 is dark and the magnet 18 is deenergized. As here 20 shown, the magnet 18 is provided with slow-release characteristics, and hence is energized at zero speed and at speeds below the critical speed. When the apparatus of Fig. 1 is used in connection with speed control systems for rail- 25 way trains, the lamp 16 may be used to indicate to the operator of the train the zero and low speed conditions, and the magnet 18 may be used to effect a control over the train brake equipment, and when so used an unsafe indication due 30 to loss of power or breakage of a part is avoided.

In Fig. 2, the circuit interrupting means is in the form of a double commutator indicated as a whole by the reference character C3, and the time limit electromagnetic means consists of a 35 single direct current relay R3. Two contact brushes 24 and 25 are mounted rigid on the shaft 1, here indicated schematically by a dotted line, the brush 24 being adapted to make engagement with a segment 26 continuously and with seg- 40 ments 27 and 28 during alternate half revolutions, and the brush 25 being adapted to make engage- 45 ment with a segment 29 continuously and with segments 30 and 31 during alternate half revolu- 50 tions. One terminal of the battery 7 is connected with the segment 26 over wire 36 and the opposite terminal of the battery is connected with the segment 29 over wire 37, and thus the brush 24 is electrically connected with one pole of the battery and the brush 25 is connected with the other pole of the battery. The right-hand ter- 55 minal of the winding of relay R3 is connected with the two segments 27 and 30 over wires 32 and 33, respectively, and the left-hand terminal of the winding of relay R3 is connected with the two segments 28 and 31 over wires 34 and 35, respectively. It follows that with the brushes 24 and 25 in the position illustrated in Fig. 2, current is supplied from the battery 7 to the winding of relay R3 over wire 36, segment 26, 60 brush 24, segment 27, wire 32, operating winding of relay R3 wire 35, segment 31, brush 25, seg- 65 ment 29, and wire 37 back to the battery; but that with the brushes 24 and 25 rotated 180° from the position illustrated, current is supplied from battery 7 over wire 36, segment 26, brush 24, segment 28, wire 34, operating winding of relay R3, wire 33, segment 30, brush 25, segment 29, and wire 37 back to the battery. It is to be noted 70 that in the first case where brushes 24 and 25 engage segments 27 and 31 the current flows through the operating winding of relay R3 in one direction, while in the second case where brushes 24 and 25 engage segments 28 and 30 the current flows through the operating wind- 75 ing of relay R3 in the opposite direction. That

is to say, during one-half revolution of the shaft 1, the relay R3 is energized with current of one polarity and during the second one-half of the revolution the relay R3 is energized with current of the opposite polarity, with the result that 5 the magnetization of the relay R3 builds up in one direction, dies away to zero, builds up in the opposite direction and dies away to zero each revolution of the shaft 1. The relay R3 is pro- 10 vided with slow pick-up characteristics similar to the relays R1 and R2, but the pick-up value of current for the relay R3 need not be relatively high as was the case in connection with relays R1 and R2. Consequently, at zero speed of shaft 15 1 the relay R3 is retained steadily picked up; at speeds below the critical speed the relay R3 is alternately picked up and released since the duration of each impulse is greater than the slow pick-up period, and since the polarity of 20 energization of the relay is reversed each half revolution; but that at speeds above the critical speed and when the duration of each impulse is less than the pick-up period, the contact 39-40 25 of relay R3 remains open. At relatively high speeds of shaft 1 the magnetization in the mag- 30 netic circuit of relay R3 is not slowly built up by the rapid successive impulses since the magnetization of the relay is reversed each half rev- 35 olution. The relay R3 governs the indication lamp 16 and the control magnet 18 by a simple 35 circuit which includes the contact 39-40 of the relay. It is clear, therefore, that the lamp 16 and magnet 18 of Fig. 2 are governed in re- 40 sponse to the speed of rotation of shaft 1 in a manner similar to that explained in connection with Fig. 1, and an unsafe indication due to loss of power or breakage of a part is avoided.

In this form of apparatus a snap action of the contact brushes 24 and 25 from engagement with one associated segment to the other segment is 40 provided. Looking at brush 24, for example, its outer end 24^a is pivoted at 96 to the inner end 24^b which is rigid on shaft 1. The outer end 24^a is held in a central position by means of two flat springs 97 and 98, the inner ends of which springs 45 are riveted at 99 to the inner end 24^b of brush 24. It is clear that the outer end 24^a of brush 24 may be turned in either direction about the pivot 96 against the force of spring 97 or 98 depending upon the direction it is turned. Assuming the 50 shaft 1 is rotated counterclockwise, as viewed in Fig. 2, the outer end 24^a strikes a stationary post 100 and is turned about the pivot 96 against the spring 98. In such position against post 100 the brush 24 is held in engagement with the seg- 55 ment 27. Upon further rotation of shaft 1 and the inner end 24^b of brush 24, the outer end 24^a is turned until it slides past the post 100 and when that position is reached the outer end 24^a is 60 snapped back to its central position due to the force of the spring 98, and the brush then makes engagement with the segment 28. It is seen therefore, that brush 24 is snapped from engagement with segment 27 to engagement with segment 28 and that shaft 1 can not stop at a 65 position where brush 24 engages both segments 27 and 28 at the same time or where it is not in engagement with either segment. When the shaft 1 has rotated one-half revolution and brush 24 encounters a stop post 101, a similar snap 70 action of brush 24 from engagement with segment 28 to engagement with segment 27 takes place. The brush 25 is constructed in a manner similar to that just described for brush 24 and has associated therewith two stop posts 102 and 75

103 and a snap action of brush 25 from engagement with segment 31 to engagement with segment 30 or vice versa is accomplished.

In the form of the invention disclosed in Fig. 5, 3, the time limit electromagnetic means consists of two relays R4 and R5, each of which is provided with slow pick-up characteristics similar to relay R3. The circuit interrupting means of Fig. 3 consists of a commutator C4 which includes 10 two brushes 41 and 42 rigid on the shaft 1, and two pair of annular segments associated with each brush. The brush 41, in addition to continuously engaging a segment 43, alternately engages the individual segments of both pair of 15 segments, the first pair of which consists of segments 44 and 45, and the second pair of which consists of segments 46 and 47, as will be readily understood by inspection of Fig. 3. In like manner, the brush 42, in addition to continuously engaging a segment 48, alternately engages a first pair of segments 49 and 50 and also alternately engages a second pair of segments 51 and 52. The battery 7 has its two terminals connected 20 with the segments 43 and 48, respectively. The opposite terminals of the winding of relay R4 are connected with the segments 44 and 45 of the first pair associated with brush 41 over wires 25 53 and 54, respectively; and are also connected with the segments 49 and 50 of the first pair 30 associated with the brush 42 over wires 55 and 56, respectively. In a similar manner, the opposite terminals of the winding of relay R5 are connected with the segments 46 and 47 of the second mentioned pair associated with the brush 35 41 over wires 57 and 58; and are connected with the segments 51 and 52 of the second mentioned pair associated with the brush 42 over wires 59 and 60. It follows that with the brushes 41 and 42 in the position illustrated in Fig. 3, current of 40 one polarity is supplied to the relay R4, but that with the brushes moved around 180° from the position illustrated, current of the opposite polarity is supplied to the relay R4. The first circuit may be traced from the battery 7 over segment 43, brush 41, segment 45, wire 54, operating 45 winding of relay R4, wire 55, segment 50, brush 42, segment 48 and back to the opposite terminal of the battery 7; and the second circuit may be traced from battery 7 over segment 50 43, brush 41, segment 44, wire 53, operating winding of relay R4, wire 55, segment 49, brush 42, segment 48 and back to the battery 7. In a like manner, current of one polarity is supplied to the winding of the relay R5 with the brushes 41 and 42 in the position illustrated, and is supplied 55 with current of the opposite polarity when the brushes 41 and 42 are rotated 180°. In this case, the first circuit includes battery 7, segment 43, brush 41, segment 47, wire 53, winding of relay 60 R5, wire 60, segment 52, brush 42, segment 48 and to the opposite terminal of the battery; and the second circuit includes battery 7, segment 43, brush 41, segment 46, wire 57, operating winding of relay R5, wire 59, segment 51, brush 42, segment 48 and back to the battery 7. It is to 65 be noted that the brushes 41 and 42 pass from one segment to the next of one pair of the segments 90° in advance of the point where they pass between the two segments of the other pair. Hence, with the apparatus constructed as shown in Fig. 3, both relays R4 and R5 are steadily 70 picked up at zero speed for all positions of the brushes 41 and 42 except at the points adjacent the two segments of a pair of segments, and in

this instance at least one of the relays is energized. It follows, therefore, that the relays R4 and R5 are each operated in response to rotation of the shaft 1 in the manner explained in connection with relay R3 of Fig. 2. 5

The relays R4 and R5 control the indication lamp 16 and the control magnet 18 by two simple parallel circuits, one of which includes the circuit controlling armature 92 of relay R4 and the other of which includes the circuit controlling 10 armature 93 of the relay R5, with the result that the indication lamp 16 and the control magnet 18 are governed by the apparatus of Fig. 3 in exactly the same manner as explained for the previous forms of the invention, and an unsafe 15 indication due to loss of power or breakage of a part is avoided.

In Fig. 4 the circuit interrupting means consists of a cam 73 rigid on shaft 1 and a pole-changing circuit controller C5, and the time limit 20 electromagnetic means includes the relay R3 the same as the apparatus of Fig. 2. The cam 73 is provided with a raised portion 74 and a depressed portion 75, each of which spans slightly less than 180°, and the two portions are joined together by 25 easy sloping surfaces 76 and 77. The cam follower 78 is biased to ride on the surface of the cam by a spring 79 as well as by its own weight. The cam follower 78 is adapted to operate the contact controlling members 80 and 81 of the 30 controller C5, the arrangement being such that with the cam follower 78 in engagement with the raised portion 74 of the cam 73, the contact members 80 and 81 are raised into engagement with front pole-changing contacts 82 and 83, 35 respectively; but that when the cam follower 78 engages the depressed portion 75 of the cam 73, the contact members 80 and 81 are down in engagement with the back pole-changing contacts 84 and 85, respectively. The contact members 40 80 and 81 are actuated by the cam follower 78 by virtue of pins 86 and 87 adapted to fit slightly elongated slots in the cam follower, and the contact members 80 and 81 are provided with compression springs 88 and 89 which are secured to 45 the outer end of the contact members and are fixed at the points 94 and 95, respectively. It is to be seen, therefore, that as the cam follower 78 rides up or down one of the sloping surfaces 76 or 77, as the case may be, and the contact members 80 and 81 are actuated from one position toward the second position, the springs 88 and 89 are first compressed and then are effective 50 to act as toggle springs to snap the contact members to the position toward which they are being moved when the mid position is reached with the result that should the shaft 1 stop at a position where the cam follower engages one of the surfaces 76 or 77, an open position of the contacts is avoided. The battery 7 is connected to the 60 contact members 80 and 81, and the opposite terminals of the winding of relay R3 are connected with the pole-changing contacts 82—83—84—85 in the usual manner, with the result that the relay R3 is energized with current of one polarity 65 during one-half revolution of the shaft 1 and is then energized with current of the opposite polarity during the other half revolution of the shaft 1. It follows that the relay R3 of Fig. 4 is steadily picked up at zero speed of the shaft 1, 70 is alternately picked up and released at speeds below the predetermined critical speed, and its armature 91 is released for all speeds above the critical speed. The control circuit for the indication lamp 16 and the control magnet 18 in- 75

cludes the armature 91 of relay R3, and hence these devices are governed by the apparatus of Fig. 4 in the same manner previously described for the earlier forms of the apparatus.

5 The several forms of speed responsive apparatus such as are here provided are each effective to actuate indicating means by simple and rugged electrical circuit devices and an unsafe indication due to a loss of power or breakage of a part 10 is avoided.

15 Although I have herein shown and described only certain forms of speed responsive apparatus embodying my invention, it is understood that various changes and modifications may be 20 made therein within the scope of the appended 15 claims without departing from the spirit and scope of my invention.

Having thus described my invention, what I 25 claim is:

20 1. Speed responsive apparatus comprising a member adapted to be rotated at different speeds, circuit controlling mechanism operated by said member and including a first pair of contacts closed during a first predetermined portion of 25 each rotation of the member and a second pair of contacts closed during a second predetermined portion of each rotation of the member, a current source, a time limit electromagnetic device including an energizing winding; a first control 30 circuit including the source, said winding and said first pair of contacts for energizing said device with current of one polarity; a second control circuit including the source, said winding and the second pair of contacts for energizing 35 the device with current of the other polarity; and an operating circuit including a contact operated by said device.

2. Speed responsive apparatus comprising a shaft adapted to be rotated at different speeds, a 40 commutator mounted on said shaft, a pair of contact brushes effective to successively engage the segments of said commutator in response to rotation of the shaft, a source of current, a time limit electromagnetic device; a first control circuit including the source, a winding of the device 45 and said brushes for supplying an impulse of current of one polarity to said device during a first predetermined portion of each rotation of the shaft; a second control circuit including the source, said winding and said brushes for supplying an impulse of current of the other polarity to said device during a second predetermined portion of each rotation of the shaft; and an indication circuit governed by said device and 55 including a contact operated in response to an impulse of current of at least a predetermined duration.

3. Speed responsive apparatus comprising a shaft adapted to be rotated at different speeds, 60 a commutator mounted on said shaft, a pair of contact brushes effective to successively engage segments of the commutator in response to rotation of the shaft, a source of current, a relay provided with slow pick-up characteristics; a first control circuit including the source, a winding of the relay and said brushes for creating a magnetic field of one polarity for said relay during one predetermined portion of each rotation of the shaft; a second control circuit including the 65 source, said relay winding and the brushes for creating a magnetic field of the other polarity for said relay during a second predetermined portion of each rotation of the shaft; and an indication circuit governed by said relay and 70 including a contact operated in response to ener-

75 gization of the relay of one or the other polarities for a duration equal to the pick-up period of the relay.

4. Speed responsive apparatus comprising a shaft adapted to be rotated at different speeds, a 5 commutator mounted on said shaft including a plurality of segments each of a predetermined length, a pair of contact brushes effective to successively engage segments of the commutator in response to rotation of the shaft, a source of current, a pair of slow acting relays; a first control circuit for each relay each of which circuits includes the source, a winding of the relay and said brushes for creating a magnetic field of one polarity for that relay during one predetermined portion of each rotation of the shaft; a second control circuit for each relay each of which circuits includes said source, the winding of the relay and said brushes for creating a magnetic field of the other polarity for that relay during a 10 second predetermined portion of each rotation of the shaft; and an operating circuit governed jointly by said relays and including a contact of each relay operated in response to energization of the relay of one or the other polarities for a 15 duration equal to the slow acting period of the relay.

5. Speed responsive apparatus comprising, a member adapted to be rotated, circuit controlling mechanism operated by said member and including a first pair of contacts closed during a first predetermined portion of each rotation of the member and a second pair of contacts closed during a second predetermined portion of each rotation of the member, a current source, a slow pick-up relay; a first control circuit including the source, a winding of said relay and said first pair of contact for energizing said relay with current of one polarity; a second control circuit including the source, a winding of said relay and said second pair of contacts for energizing said relay with current of the other polarity; and an operating circuit including a front contact of said relay.

6. Speed responsive apparatus comprising a member adapted to be rotated, circuit controlling mechanism operated by said member and including a first contact closed only during a first portion of each rotation of said member and a second contact closed only during a second predetermined portion of each rotation of said member, a current source, a slow pick-up relay; a first control circuit including the source, a winding of said relay and the first contact and effective to create a magnetic field of one polarity for said relay; a second control circuit including the source, a winding of said relay and the second contact and effective to create a magnetic field of the other polarity for said relay, and an operating circuit including a front contact of said relay.

7. Speed responsive apparatus comprising a member adapted to be rotated, a first contact mechanism operated by said member and closed only during a first predetermined portion of each rotation of said member, a second contact mechanism operated by said member and closed only during a second predetermined portion of each rotation of said member, a current source, a slow pick-up relay, a first control circuit for energizing said relay including the source and said first contact mechanism and effective to create a magnetic field in the relay of one polarity, a second control circuit for energizing said relay including the source and said second contact mecha-

nism and effective to create a magnetic field of the other polarity in said relay whereby said relay is picked up only at substantially zero speed of said member, and an operating circuit controlled by said relay.

8. Speed responsive apparatus comprising, a member adapted to be rotated and having formed thereon a raised portion and a depressed portion, an operating element biased to ride on said portions of the member, a first pair of contacts controlled by said element and closed only when said element rides on the depressed portion, a second pair of contacts controlled by said element and closed only when said element rides on the raised portion of said member, a current source, a slow pick-up relay; a first control circuit including, the source, the winding of the relay and said first pair of contacts to energize the relay with current of one polarity; a second control circuit including the source, the winding of the relay and said second pair of contacts to energize the relay with current of the other polarity whereby said relay is picked up only at substantially zero speeds of said member, and an operating circuit controlled by said relay.

9. Speed responsive apparatus comprising a member adapted to be actuated through an operating cycle at different speeds, circuit controlling mechanism operated by said member and including a first contact closed during a fixed portion of each cycle and a second contact closed during substantially the remaining portion of each cycle, an electroresponsive device including a contact which is operated a predetermined time interval subsequent to initiating energization of said device, a first control circuit including a current source and said first contact of said mechanism for energizing said device with current of one polarity, a second control circuit including a current source and said second contact of said mechanism for energizing said device with current of the opposite polarity; whereby energiza-

tion of said device by current of one polarity is initiated, this energization is reduced to zero and energization of the device by current of the opposite polarity is initiated during each cycle of operation of said member; and an operating circuit including the contact of said device when operated.

10. Speed responsive apparatus comprising a member adapted to be actuated through an operating cycle at different speeds, circuit controlling mechanism operated by said member and including a first contact closed during a first predetermined portion of each cycle and a second contact closed during a second predetermined portion of each cycle, a current source, a relay; a first control circuit including the source, a winding of said relay and the first contact of said mechanism and effective to create a magnetic field of one polarity for said relay; a second control circuit including the source, a winding of the relay and the second contact of said mechanism and effective to create a magnetic field of the reverse polarity for said relay, and an operating circuit including a contact operated by said relay.

11. Speed responsive apparatus comprising a member adapted to be actuated through an operating cycle at different speeds, circuit controlling mechanism operated by said member and including a first contact closed during a predetermined portion of the cycle and a second contact closed during substantially the remaining portion of the cycle, a current source, a relay; a first control circuit including the current source, a winding of the relay and the first contact of said mechanism and effective to create a magnetic field of one polarity for said relay; a second control circuit including the source, a winding of the relay and the second contact of said mechanism and effective to create a magnetic field of the opposite polarity of said relay, and an operating circuit including a contact operated by said relay.
